DESIGN.

No. 31,105.

Patented June 27, 1899.

C. A. MICHAELS.

GAME BOARD.

(Application filed Dec. 10, 1898.)

UNITED STATES PATENT OFFICE.

CHAUNCEY A. MICHAELS, OF FREMONT, OHIO.

DESIGN FOR A GAME-BOARD.

SPECIFICATION forming part of Design No. 31,105, dated June 27, 1899.

Application filed December 10, 1898. Serial No. 698,899. Term of patent 3½ years.

To all whom it may concern:

Be it known that I, CHAUNCEY A. MICHAELS, a citizen of the United States, and a resident of Fremont, Sandusky county, Ohio, have invented a new and original Design for a Game-Board having shape or configuration as shown in the accompanying drawing.

The characteristic feature of my game-board is that amusement is therein combined with instruction, the relative positions in camp of the various regiments encamped at Chickamauga in the early part of the season A. D. 1898 being shown upon the board and the player being made in the game to visit each of the several regiments.

Referring to the drawing herewith, the several circles lettered, respectively, W, R, S, and G represent starting-points for the players engaged in the game, and the spaces with which they are connected, lettered, respectively, W', R', S', and G', represent safety-

spaces. The several crosses + in the spaces lettered H represent the location of hospitals. Spaces lettered G H represent the location of guard-houses. The spaces lettered S show 25 the location of saloons. The squares H', H², H³, and H⁴ at the corners represent "homes" for the several players. The small circles within the spaces and numbered "1" to "45," inclusive, represent approximately the location of the individual regiments. 30

Having now fully described my invention, what I claim as new, and pray Letters Patent for, is—

The design for a game-board substantially 35 as shown and described.

December 1, 1898.

C. A. MICHAELS.
